UNITED STATES PATENT OFFICE.

GEORGE W. KLAGES, OF PITTSBURGH, PENNSYLVANIA.

SHEET-GLASS-CUTTER HOLDER.

1,301,950.

Specification of Letters Patent. Patented Apr. 29, 1919.

Application filed September 21, 1916. Serial No. 121,380.

To all whom it may concern:

Be it known that I, GEORGE W. KLAGES, a citizen of the United States, residing at Pittsburgh, in the county of Allegheny and

5 State of Pennsylvania, have invented a new and useful Improvement in Sheet-Glass-Cutter Holders, of which the following is a full, clear, and exact description, reference being had to the accompanying drawings, forming part of this specification, in which—

Figure 1 is a side elevation of one form of diamond holder built in accordance with my invention, showing the gage in position 15 for cutting the diamond point.

Fig. 2 is a plan view with parts in section, as indicated on the line II—II of Fig. 1.

Fig. 3 is a perspective view of the angle 20 piece for connecting the carrier for the diamond holder to the holding bar.

Fig. 4 is an end view of the carrier, showing the diamond holder in position.

Fig. 5 is an end view of the collar for 25 supporting the angle piece shown in Fig. 3; and

Fig. 6 is a perspective view of the gage.

This invention relates to an improvement 30 in tool holders, and is more particularly designed for holding diamond points for sheet glass cutting machines.

The object of my invention is to provide a cheap and efficient device of this character which is so arranged that the diamond point 35 can first be set by means of a gage to its proper position and lined up to make the cut, and then secured in its adjusted position. After the diamond has been set to its position with relation to the gage, the holder 40 therefor can then be adjusted in two directions, one of which is approximately at right angles to the other, about an axis which is approximately coincident with the cutting point of the diamond.

45 By this arrangement I am enabled to first set the cutting point by means of a gage and line up the face of the diamond in the direction of its travel; and at the same time provide means for universally adjusting the 50 diamond holder about axes which are coincident with the point of the diamond without shifting the position of said point.

The precise nature of my invention will be best understood by reference to the accompanying drawings, it being premised, however, that various changes may be made

in the details of construction and arrangement of the various parts, without departing from the spirit and scope of my invention as defined in the appended claims.

60

Referring to the drawings, the reference character 2 designates the holding bar which may be graduated in any desired manner, and which is of the proper shape for attaching it to the machine on which it is to be used. Connected to one end of this bar is a collar 4, which is fixedly secured thereto by means of a through pin 5, although it will readily be understood by those familiar with the art that the collar may be secured 65 in various other ways. This collar 4 is provided with an arc-shaped projection 6. 7 is an angle member having an arc-shaped slot 8 for the reception of the rounded end of the bar 2, and is also provided with an 70 arc-shaped slot 9 for the reception of the arc-shaped projection 6 on the collar 4. 10 is a nut on the threaded end of the bar 2 for securing the angle piece 7 in position thereon, and interposed between the nut 10 75 and the angle piece is a washer 11. The other arm of the angle piece 7 is provided with an arc-shaped slot 12, similar to the slot 8, as well as an arc-shaped slot 13, which is similar to the arc-shaped slot 9, and which 80 are adapted for securing the carrier 14 in position on the angle piece.

This carrier 14 is provided with a through opening 15 which is arranged to receive a circular diamond holder 16, and which is 85 secured in position by means of a screw 17. The upper end of this diamond holder is provided with a knurled head 18, while the lower end is provided with a suitable cavity in which is secured the diamond 19.

90 The carrier 14 is provided with a screw stem 20 which is arranged to pass through the slot 12, and 21 is a nut for securing the carrier in position on the angle piece 7. 22 is a washer interposed between the angle 100 piece and the nut 21. The carrier 14 is also provided with an arc-shaped projection 23 which is seated in the arc-shaped slot 13, which projection is similar to the projection 6 on the collar 4. The angle member 7 and 105 the carrier 14, with their connections, form a universal adjustable support for the diamond holder which will permit the adjustment of the holder in two planes at right angles to each other about the point of the 110 diamond 19, to change the angle of the diamond.

24 is a gage for setting the diamond point, and which is provided with a recess 25 adapted to receive the squared portion of the bar 2. This gage is also provided with 5 a downwardly and forwardly extending arm 26, which is provided with a diamond setting surface 27.

When it is desired to set the diamond holder in the device, the gage is applied to 10 the bar as shown in Figs. 1 and 2. The diamond holder 16 is then passed through the carrier and the point of the diamond is brought into contact with the surface 27 of the gage. The holder 16 is then rotated to 15 place the diamond in proper cutting position, after which the screw 17 is tightened to secure the holder in position in the carrier. The gage 26 can then be removed, and the nuts 10 and 21 are tightened to rigidly 20 secure the various parts to each other. The device may then be tried, and if it does not make the proper cut, the carrier 14 may be adjusted on the angle piece 7, while the angle piece 7 may be adjusted on the collar 4 25 on the projections 23 and 6. Both of these adjustments being approximately on arcs struck from a center which is approximately coincident with the point of the diamond, the arrangement being such that the holder 30 16 may be adjusted in directions at right angles to each other without approximately changing the position of the point of the diamond.

It will readily be understood by those 35 familiar with the art that other cutting tools than diamonds may be secured in a holder of this character.

The advantages of my invention result 40 from the provision of a tool holder having supporting devices which are arranged to be adjusted in one or more directions about the cutting or working point of the tool without changing the position of the point thereof.

45 I claim:

1. A device of the character described comprising a diamond holder, a carrier therefor, said diamond holder being arranged to be adjusted within the carrier, a 50 support for the carrier, said support having a guide for the carrier arranged to permit the carrier and holder to be adjusted about the point of the diamond, means to secure the carrier in its adjusted position to the support, a holding bar, supporting connections 55 between the holding bar and the support arranged to permit the support to be adjusted about the point of the diamond at right angles to the adjustment of the carrier on the

support, and means for securing the support 60 in its adjusted position, substantially as described.

2. A device of the character described, comprising supporting means, a holder for a diamond adjustably secured in the supporting means, a holding bar for the supporting means, and a universal connection between the holding bar and the supporting means arranged to permit the diamond holder to be adjusted in two directions at 70 right angles to each other about the diamond point as a center, substantially as described.

3. A device of the character described, comprising supporting means, a holder for a diamond adjustably secured in the supporting means, a holding bar for the supporting means, and a universal connection between the holding bar and the supporting means arranged to permit the diamond holder to be adjusted in two directions at 75 right angles to each other about the diamond point as a center, said holding bar being arranged to fixedly support a gage for 80 setting the point of the diamond, substantially as described.

4. A device of the character described, comprising a holding bar, an angular member supported thereon, means for adjustably securing said member to the holding bar, a carrier adjustably secured to the angular member, and a diamond holder adjustably secured to the carrier, the connections between the carrier and the angular member to the holding bar being such that the diamond holder may be adjusted in two planes 90 at right angles to each other about the point of the diamond, substantially as described.

5. A cutter holder, comprising a holding member, a supporting head connected thereto, an angle piece connected to said supporting head, there being an arc-shaped tongue-and-groove connection between said angle piece and the head, a cutter carrier connected to the angle piece, there being an arc-shaped tongue-and-groove connection between the angle piece and the carrier, means for securing the angle piece to the holding member, means for securing the carrier to the angle piece, and a cutting tool adjustably mounted in the carrier; substantially 105 as described.

In testimony whereof, I have hereunto set my hand.

GEORGE W. KLAGES.
